UNITED STATES PATENT OFFICE.

DANIEL NEI, OF GRAND RAPIDS, MICHIGAN, ASSIGNOR OF ONE-HALF TO
JOHN H. DEAN, OF SAME PLACE.

BICYCLE-ALARM.

SPECIFICATION forming part of Letters Patent No. 636,833, dated November 14, 1899.

Application filed April 3, 1899. Serial No. 711,622. (No model.)

To all whom it may concern:

Be it known that I, DANIEL NEI, a citizen of the United States, residing at Grand Rapids, in the county of Kent and State of Michigan, have invented certain new and useful Improvements in Bicycle-Alarms, of which the following is a specification.

My invention relates to improvements in revoluble grips attached to and arranged for ringing bicycle-bells; and its objects are, first, to provide a revoluble grip that may be applied to ring any of the various forms of bicycle-bells, whether constructed to be actuated with a reciprocating or a revoluble actuating mechanism, and, second, to avert the danger of straining or breaking the lever upon a reciprocating bell or of allowing the grip to revolve too far on a revoluble bell. I attain these objects by the mechanism illustrated in the accompanying drawings, in which—

Figure 1 is a longitudinal section of a grip and the end of a handle-bar on the line $x x$ of Fig. 2. Fig. 2 is a side view of my grip, showing its connection with a revoluble bell. Fig. 3 shows the same connected with a reciprocating bell. Fig. 4 is an end view of a grip, showing the stop mechanism. Fig. 5 is a plan and Fig. 6 is a side view of the jam-nut or packing-screw that holds the packing in the end of the grip-sleeve, and Fig. 7 is an end view of the clamp that engages the inner surface of the handle-bar to hold the grip securely thereto.

Similar letters refer to similar parts throughout the several views.

A represents the end of the handle-bar.

B represents the grip, and I represents the bell. In the construction of this grip I form a metallic sleeve D, somewhat larger than the external diameter of the handle-bar, so that it will turn freely thereon without coming in contact therewith. The outer end of this sleeve is formed to cover the end of the handle-bar and is provided with a central aperture a', through which the screw F passes, forming a bearing to perfectly center the end of the grip upon the handle-bar and hold the sleeve from contact with the end thereof. This screw passes through the spool C C' and the hub of the spring-clamp E, which is provided with a screw-thread for the reception

of said screw and by means of which it may be drawn upon the inclined surface of the end C' of the spool with sufficient force to cause it to press heavily against the inner surface of the handle-bar and engage therewith to hold the grip securely to place. The other end of this sleeve is spun out to form the shoulder and cup D', and the inner surface of the cup, beyond the shoulder, is provided with a screw-thread arranged to receive and mesh freely with the screw-thread on the surface of the jam-nut G. (Shown in Fig. 6.) I place a gasket, of leather or other suitable material, in this cup, as shown at H in Fig. 1, and force it to place with the jam-nut, by means of which I can exert more or less pressure, as the case may demand. This gasket is designed, first, to act as a bearing to support this end of the grip and prevent it from coming in contact with the handle-bar; second, to produce sufficient friction, so that there will be no inconvenience incurred by reason of the grip turning too easily; third, to prevent water or oil flowing through between the grip-sleeve and the handle-bar, and, fourth, to form a smooth bearing at this line and prevent the grip from trembling. At the end or edge of this cup I form a series of fine gear-teeth d', arranged to engage the teeth on the periphery of the rotary actuating-wheel I' upon rotary ringing-gear for bells, and also a short arm d'', to which I pivotally attach one end of the connecting-link i, the opposite end of which is attached to the lever i' of a lever-actuated or reciprocating bell, so that a slight turning of the grip in the direction of the arrow in Fig. 4 will sound the bell upon one stroke and the spring-actuated return of the lever will ring the bell upon the other stroke of the hammer and will draw the grip around to its normal position. (Indicated in Fig. 4.)

To avert the danger of straining or breaking the link i or the lever i' or of turning the grip too far when used with a rotary bell, I place a short pin c on the surface of the back end of the spool, which projects out just far enough to pass through the end of the sleeve D, and in this end I form a short slot d in position to receive the pin and allow the grip to turn only the length of the slot less the size of the pin.

To facilitate placing the spool in place in the handle-bar and to prevent it from turning when screwing the clamp to place, I form sharp inclined lugs c'' on the end C of the 5 spool and lugs, as indicated at c' , on the end C' of the spool, it being understood that the spool is made in two pieces, the portions C and C' being separate and detachable.

The grip may be completed with corkoline, 10 leather, or any other suitable material, the ends being protected by ferrules b b' in the usual manner, the ferrule b being provided with an aperture for the reception of the screw F. The body of the screw F is slim 15 and is provided adjacent to the head with a shoulder of a proper length to pass through the end of the sleeve and the ferrule and clamp the grip firmly to the handle-bar and at the same time allow the grip to turn freely 20 on the handle-bar.

The back wall or shoulder of the cup D' is slightly inclined or angling, so that the forcing of the gasket H against it will at the same time force it toward the handle-bar, so that 25 the degree of friction induced by the gasket may be controlled at pleasure.

Having thus fully described my invention, what I claim as new, and desire to secure by Letters Patent of the United States, is—

30 1. In combination with the handle-bar of a bicycle, a revoluble grip, a supporting-sleeve within said grip, the outer end of said sleeve closed and the inner end expanded to form a seat for a packing or gasket, and a receptacle 35 for a jam-nut, a clamp within said handle-bar, a screw to engage the clamp to hold the grip to place, a connection between the grip and the bicycle-bell, a slot through the closed end of the sleeve, and a pin projecting from 40 the end of the spool to engage therewith to govern the motion of the grip, substantially as, and for the purpose set forth.

2. In combination, a handle-bar, a grip, and a bell; a connection between the grip and the 45 bell, a supporting-sleeve within the grip, a chamber in the end of said sleeve, a pliable packing within said chamber, a jam-nut to screw into said chamber to regulate the pressure of the packing upon the handle-bar, an

inclined shoulder to receive the packing, and 50 a stop for limiting the motion of the grip, substantially as and for the purpose set forth.

3. In combination with a handle-bar and bell of a bicycle, a revoluble grip secured to encircle the end of the handle-bar, an annular gear-wheel on the grip to engage the actuating-wheel of the bell, a spool fitted to adjust itself to the inner diameter of the handle-bar, a flaring clamp fitted to be expanded by the end of the spool, and a screw passing 55 through the ferrule of the grip, the spool and into the hub of the clamp to secure the clamp and spool to the handle-bar, and a shoulder on the screw to bear upon the end of the spool so that the clamp may be firmly set in the 60 handle-bar without interfering with the revoluble motion of the grip, substantially as and for the purpose set forth.

4. In combination with the handle-bar and bell of a bicycle, a revoluble grip secured to 70 encircle the end of the handle-bar and connected to ring the bell when revolved, a spool, a clamp, and a screw having a shoulder to secure the clamp inside of the handle-bar without binding the grip, and lugs and inclines on 75 the spool to prevent it from turning in the handle-bar, substantially as and for the purpose set forth.

5. In combination with a handle-bar and bell of a bicycle, a revoluble grip secured to 80 encircle the handle-bar and having an annular gear fitted to mesh with the actuating-wheel of a bell, and an expansible clutch within the handle-bar to secure the grip thereon, substantially as and for the purpose set forth. 85

6. In combination with a handle-bar, and a revoluble grip for ringing a bicycle-bell, a spool, an expansible clutch, a screw having a shoulder to engage the spool and allow the grip to turn freely, and lugs on the spool to 90 prevent it turning in the handle-bar, substantially as and for the purpose set forth.

Signed at Grand Rapids, Michigan, March 4, 1899.

DANIEL NEI.
